UNITED STATES PATENT OFFICE.

JEAN RÉOL, OF ALAIS, FRANCE, ASSIGNOR TO SOCIÉTÉ DE CONSTRUCTIONS MÉCANIQUES D'ALAIS, OF ALAIS, FRANCE, A CORPORATION.

CONTINUOUS DRYING-KILN WITH VERTICAL AXIS.

1,093,206.

Specification of Letters Patent. Patented Apr. 14, 1914.

Application filed December 24, 1912. Serial No. 738,438.

To all whom it may concern:

Be it known that I, JEAN RÉOL, engineer, residing at Alais, Department of Gard, France, have invented new and useful Improvements in Continuous Drying-Kilns with Vertical Axes, which improvements are fully set forth in the following specification.

The present invention relates to improvements in kilns, particularly that class of drying kilns in which the products to be dried, travel in successive cascades in the direction opposite to that of the hot gases coming from any desired source; the hot gases being drawn in by a fan and forced either outside or under the grate of an independent furnace or into a branch, so as to be recuperated by means of a desired device.

This invention relates to certain improvements effected in the said drying kiln.

In order to make the following explanation as clear as possible, a construction of the improved apparatus is illustrated by way of example in the accompanying drawings, in which—

Figure 1 is a vertical section of the apparatus, and Figs. 2 and 3 show on two different scales the inner development of the apparatus. Fig. 4 is a horizontal cross-section.

The distribution of the material and its successive falls from the upper to the bottom part take place in the same way as in the known apparatus.

Hot air is circulated in the direction opposite to that of the material by means of the following device constituting one of the improvements forming the subject of the invention. The principle consists in directing the hot gases to the exact points where take place the falls of the material. To that end, the central spindle is provided at each floor with vertical scrapers *a* of a suitable height. To the said vertical scrapers are se-

cured horizontal sectors *b* having the outline *c d e f* (Fig. 4). The fixed soles *g* comprise ribs *h* forming a vertical partition between the fixed sole and the horizontal sectors secured to the scrapers *a* of the row below. The central spindle, in its movement of rotation in the direction of the arrow (Fig. 4), drives the vertical blades and with them the horizontal sectors, so that the latter at a given moment lie under the ribs *h* so as to form an obturator and force the hot gases to pass exactly through the only open orifice, namely that at which takes place the fall of the material, which fall is produced by a scraper *a*. The play of the obturators and of the scrapers is automatic and continuous. The gases escape at *h* and pass then through a cyclone or dust separator of a well known type. Finally the fan can be a blower, and the casing of the kiln can have the cylindro-conical shape shown in Fig. 1, so that all the cross-sections of passage for the gases should go increasing.

Claim—

In a vertical drying kiln the combination of a central vertical spindle with a plurality of superposed, spaced platforms alternately arranged around said spindle, vertical scrapers upon each of said platforms, horizontal sections secured to said scrapers, and vertical ribs secured to the underside of said platforms forming at given moments an obturator with said sections for forcing the hot gases to pass through the falling material removed from said platforms by said scrapers in an automatical and continuous operation.

In testimony whereof I have signed this specification in the presence of the subscribing witnesses.

JEAN RÉOL.
